UNITED STATES PATENT OFFICE.

WOODBURY T. OLIVER, OF NEWPORT NEWS, VIRGINIA.

BOAT RAISING AND LOWERING MECHANISM.

1,237,085.

Specification of Letters Patent. Patented Aug. 14, 1917.

Application filed August 8, 1916. Serial No. 113,789.

To all whom it may concern:

Be it known that I, WOODBURY T. OLIVER, a citizen of the United States, residing at Newport News, in the county of Warwick 5 and State of Virginia, have invented new and useful Improvements in Boat Raising and Lowering Mechanism, of which the following is a specification.

This invention relates to a mechanism for 10 raising and lowering life boats, and its primary object is to provide a raising and lowering apparatus including means, automatically operable upon the manual actuation of a controlling device, whereby the boat will 15 be incidentally released for a lowering action.

A further object of the invention is to provide an apparatus of the character described 20 including a lowering mechanism *per se* automatically thrown into action upon the release of the boat and its movement to a primary position to effect the lowering of the boat and its maintenance in position in line 25 within deck for the embarkation of passengers.

A further object of the invention is to provide an apparatus of the character described which is simple of construction, reliable and efficient in action, and wherein 30 the lowering movements of the boat are governed and controlled by a reliable and efficient type of retarding and cushioning devices.

The invention consists of the features of 35 construction, combination and arrangement of parts hereinafter fully described and claimed, reference being had to the accompanying drawings in which:—

Figure 1 is a longitudinal section through 40 a deck of a vessel showing in side elevation a boat in connection with my improved raising and lowering mechanism, as the parts appear in normal position.

Fig. 2 is a transverse section through a 45 portion of the ship, showing in full lines the normal position of the boat and raising and lowering mechanism, and in dotted lines certain positions of the boat when released for the lowering action.

Fig. 3 is a side elevation on an enlarged scale of one of the davit frames and arms, and showing the davit arm as fully moved outward.

Fig. 4 is a sectional plan view of the same. 50 Fig. 5 is a view of the cushioning device shown in Figs. 3 and 4 on an enlarged scale.

Fig. 6 is a fragmentary detail view of the boat and one of its deck supports.

Fig. 7 is a view showing on an enlarged scale the means for locking and releasing 60 the controlling drums of the davit arms.

Fig. 8 is a detail section of one of the davit arms, the brake mechanism, and the associated locking means.

Fig. 9 is a detail section on the line 9—9 of Fig. 8.

Referring to the drawings, 1 designates a life boat which is adapted to be normally supported by chocks or cradles 2 fixed to the deck 3 of the ship, each cradle having a segmental surface 4, extending upwardly and rearwardly from the forward portion 5 thereof on an arc of a desired radius, to support the boat on the inboard side of the keel line, leaving the boat free to move outward 75 when released. The cradles may be provided with friction rollers 6 to adapt the boat to move into and out of supporting position with a desired ease and freedom.

Fixed to the deck 3 are frame elements 7 arranged a somewhat greater distance apart than the length of the boat 8 resting in the supports 2, and each of these frame elements is provided with a slotted guideway 9, the end walls of which form stops 10 and 11. 85

Pivotedly mounted at its lower end, as shown at 12 to the base of each frame element is a davit arm 13, and the upper or free ends of said arms are provided with the usual outwardly curved terminals 14 from 90 which the boat is directly supported, as hereinafter described. The davit arms normally bear against the stops 10 and are disposed in a vertical position, and are movable outwardly to an inclined position to the extent 95 limited by the stops 11, in which position the arms are arranged to permit the lowering or raising of the boat beyond the line of the side of the vessel, the two positions of the davit arms being illustrated clearly in 100 full and dotted lines in Fig. 2.

The boat is normally held seated in the concaved seats 4 of the supports 2 by means of fastenings, consisting of lashings of ropes or cables 15, each fastened at one end to the 105 deck, as shown at 16, and having at its opposite or free end a loop or eye 17, said fastenings being passed about the bow and stern portions of the boat to secure the same against outward displacement from the supports. Fixed to the deck are bifurcated and perforated keeper brackets 18 adapted to

receive the eyes 17 of the fastenings 15, and also to receive locking and releasing rods 19 which engage the eyes and hold the fastenings 15 in position. The adjacent or relatively inner ends of these rods are connected with a pivoted locking and releasing lever 20, above and below the pivotal point thereof, and this lever 20 is provided with a spring actuated dog 21 to interlock with notches 22 and 23 in a locking segment 24, by which the lever may be secured in locking and releasing positions.

The boat is thus normally held fastened in the supports by lashings 15, but it will be understood that by simply shifting the lever 20 from locking to releasing position the rods 19 will be operated to withdraw them from engagement with the eyes 17, thus disconnecting the ends of the lashings and allowing the boat to swing outward beyond the seat supports 2 and also beyond the line of the adjacent side of the vessel, as hereinafter described by the force of gravity, an automatic movement of the boat to a position ready for lowering being thus obtained. In this operation the davit arms 13 swing in the guideways 9 from contact with the shoulders 10 to contact with the shoulders 11, as will be readily understood. The boat is supported from the curved ends 14 of the davit arms by suitable tackle comprising cables 25 and 26, each secured at one end with a double pulley block 27 to the co-acting davit arm, and thence passing in the form of a loop 28 around said pulley block and a guide sheave or pulley 29 on the adjacent end of the boat, the construction and arrangement being such as to permit contraction and expansion of the loop in the paying out of the cables to lower the boat and the winding up of the cables to raise the boat back to normal position. The opposite ends of the respective cables pass around guide sheaves 30 on the deck and are secured to drums 31 and 32 on a winding shaft 33, controlled in operation as herein-after described.

In order to prevent too violent motion of the davit arms in launching the boat, and also to enable the davit arms to be moved backward to normal position, I provide winding and cushioning devices for co-operation with each davit arm. Each of these winding devices comprises a winding cable 34 secured at one end to the davit arm, passing intermediately over a guide pulley 35 and secured and wound at its opposite end around a drum 36 on a shaft 37 to which is also fixed a worm gear 38. Meshing with this worm gear 38 is a worm 39 mounted on a shaft 40 journaled in vertically movable bearings and having an angular end portion 41 for the attachment of a crank or other tool whereby winding motion may be communicated with the drum to retract

or move the davit arms back from advance to normal position. The worm shafts are adjustable by means of links 42 to slide the worms into and out of engagement with the worm wheels, and each link is connected with a crank arm 43 on a rock shaft 44 having another crank arm 45, the crank arms 45 of the respective links being coupled by connecting rods 46 to the locking and releasing rods 19 whereby when said locking and releasing rods are released the connecting rods will be simultaneously drawn upon to lower the worms to free the drum 36 and cable 34 for unwinding motion, while on the contrary when the locking and releasing rods are again moved to locking position the worms will be moved into engagement with the worm wheels, so that the drums may be rotated to wind up the cables for the retraction of the davit arms.

The means for cushioning and controlling the outward movement of the davit arms comprises a lug 47 on each davit arm to which is pivoted one end of a piston rod 48, fixed at its opposite end to a piston 49 movable within the cylinder 50 pivoted at its outer and lower end to the davit arm frame, as shown at 51. The cylinder is provided with a by-pass groove 52 of greatest depth at the top of the cylinder and thence gradually diminishing in depth toward the bottom of the cylinder, said groove terminating above the bottom of the cylinder, while the piston is provided with restricted ducts or passages 53. The cylinder contains a cushioning fluid or liquid 54, such as compressed air or oil, which is normally arranged between the piston and lower end of the cylinder. When the davits swing outward under the weight of the released boat, the pistons move downward in the cylinder and check and control the outward movements of the davit arms, the groove ducts allowing the fluid to slowly pass by and through the piston from the lower to the upper end of the cylinder, whereby a retarded downward travel of each piston is obtained to prevent slamming and to insure ease of action. As each by-pass groove allows rapid movement of the oil from the bottom to the top of the cylinder it will be evident that the davit arms will be permitted to freely move outward at the start for a portion of their swing and then to travel more slowly, the pistons passing beyond the shallow ends of the grooves before the arms reach the limit of their movement and thereby trapping a portion of the fluid between the pistons and lower ends of the cylinders for a cushioning action, such oil then escaping slowly through the ducts in the pistons to allow the arms to move out to a full degree. On the reverse movement of the pistons a retarding action is established which gradually becomes re-

duced by reason of the increasing depth of the by-pass groove, thus permitting the arms to be moved back without the necessity of employing an excessive degree of power.

5 The pivoted ends of the arm 13 associated with the frame element 7 on which the drums 31 and 32 are mounted is provided at its lower end with a lug 55 to which is 10 pivoted a link 56 connected with a locking pin or bolt 57 movable in a keeper 58 similar in construction to the keepers 18. This keeper 58 is adapted to receive the apertured free end of the arm 59 of a bell crank 15 lever 60 to the opposite arm 61 of which is connected a brake band 62 passing around a brake drum 63 on the drum shaft 33, by means of which the brake drum will be normally held locked to hold the winding 20 drums and raising and lowering cables from action until the boat has been released and has swung outward by the gravity of its own weight to the dotted line position A shown in Fig. 2 beyond the line of the 25 side of the vessel. When the boat reaches this position the davit arm 13 controlling the latch which has moved to such a position as to cause the retraction of the locking pin or bolt 57, thus releasing the brake lever and 30 permitting the brake band to loosen and release the cable for unwinding movement, so that the boat may descend automatically by gravity to the lowered position shown at A' in dotted lines in Fig. 2. Hence when 35 the bolt is released by manual operation of the lever 20 and it swings automatically first to the clear position A through the swinging movements of the davit arms, and then when this position is reached the normally 40 locked winding mechanism will be unlocked and thus permit the winding cables to have movement so that the boat will automatically descend further to the position A'. This position may bring it into 45 alinement with any deck of the vessel, so that while it is held in such position the passengers or crew may embark with safety preliminarily to the lowering of the boat into the water. For the purpose of controlling and cushioning the downward 50 movement of the bolt between positions A and A', I provide a cushioning cylinder 64 and piston 66 connected with a crank 67 on the winding drum shaft, and which piston 55 is provided with oil passages, whereby the unwinding motion of the drums will be governed to let out the cables gently and easily for a gradual and regulated descent of the boat as will be readily understood.

60 I claim:

1. In a boat launching mechanism the combination with a means for normally supporting a boat, gravity actuated davit arms mounted for swinging movement, a 65 lowering mechanism mounted on the free

ends of said davit arms and adapted to be connected to a boat on said supporting means, manually operated winding means for retracting said davit arms and adapted to be locked against the influence of said 70 davit arms, means in operable relation with said davit arms for locking said lowering mechanism when said davit arm is in normal position, and a manually operated means for simultaneously releasing a boat 75 from said support and for releasing said winding means.

2. In a boat launching mechanism the combination with a chock for supporting the boat, means for securing a boat upon 80 said chocks, gravity actuated davit arms mounted for swinging movement, a lowering mechanism mounted on the free ends of said davit arms and adapted to engage a boat for lowering the same, automatic means 85 for controlling the rate of speed at which said lowering mechanism operates, means for controlling the rate of speed at which said davit arms are swung, manually operated means for retracting said davit arms 90 and adapted to be locked against movement under the influence of said davit arms, locking means for said lowering means actuated by the movement of said davit arms, and a manually operated means for simultaneously 95 releasing said securing means and said retracting means.

3. In a boat launching mechanism the combination with a frame, a gravity actuated davit arm pivotally mounted in said 100 frame and having a limited movement, a drum rotatably mounted in said frame, a worm gear in driving relation with said drum, a worm adapted to be manually rotated, bearings for said worm movably 105 mounted in said frame whereby said worm may be engaged and disengaged with said worm gear, manually operated means for positioning said bearings, and a cable having its one end affixed to said davit arm and 110 its other end affixed to said drum.

4. In a boat launching mechanism the combination with means for supporting a boat, manually operated means for releasing a boat on said support, gravity actuated 115 davit arms, lowering mechanism mounted on the free ends of said davit arms and adapted to engage a boat on said supporting means, a drum for each davit and mounted for rotation, worm gears in driving relation with respective drums, worms adapted to be manually rotated, movably mounted bearings for each worm whereby said worms may be engaged and disengaged 120 with their free respective worm gears, means for positioning said bearings, cables having one of their ends affixed to their respective davit arms and having their other ends affixed to their respective drums, and means in operable connection with said 125 130

bearings and said means for releasing a boat on said support whereby said worms are disengaged from their respective worm gears when the boat is released.

5. In a boat launching mechanism, chocks for supporting a boat, means for securing a boat upon said chocks, gravity actuated davit arms mounted for swinging movement, lowering mechanism mounted on the free ends of said davit arms and adapted to engage a boat on said chocks, automatic means for controlling the rate of speed at which said lowering mechanism operates, means for controlling the rate of speed at which said davit arms swing, a drum for each davit arm mounted for rotation, worm gears in driving relation with respective drums, worms adapted to be manually rotated, movably mounted bearings for each

worm whereby said worm may be engaged 20 and disengaged with its respective worm gear, means for positioning said bearings, cables having one of their ends affixed to their respective davit arms and having their other ends affixed to their respective 25 drums, locking means for said lowering means actuated by the movement of said davit arms, manually operated means for simultaneously releasing a boat on said support and for disengaging said worms from 30 their respective worm gears.

In testimony whereof I affix my signature in presence of two witnesses.

WOODBURY T. OLIVER.
